COMPOSITE SEQUENCE FILTER FOR
CURRENT CIRCUITS

William K. Sonnemann, Roselle Park, N. J., assignor to Westinghouse Electric Corporation, East Pittsburgh, Pa., a corporation of Pennsylvania

Application April 4, 1947, Serial No. 739,469

4 Claims. (Cl. 171—97)

1

My invention relates to a single sequence-segregating network having a response which is controllably proportional, with any desired constants, to any two, or all three, of the positive-, negative-, and zero-sequence components of a three-phase current.

An object of my invention is to provide an improved network of the type just described, which is somewhat more flexible in design, than previously known networks, and which utilizes impedance-elements which make a more efficient use of material and mounting-space.

My invention is an improvement over the sequence-networks which are shown on pages 248 and 249 of the Electrical Transmission and Distribution Reference Book, 1942 edition; a Harder Patent 2,183,646, granted December 19, 1939; and my previously filed copending application Serial No. 591,079, filed April 30, 1945, for Control-systems.

Composite sequence-segregating networks, or networks which respond, in different magnitudes, to a plurality of different phase-sequence components of the input-current, are useful in relay-systems or control-systems which are intended to respond to a plurality of different kinds of faults, which may affect different phases or combinations of phases of the impressed line-current. Thus, the Harder patent showed a composite network having a heavily weighted response to the zero-sequence current-component, and having a relatively small response to the positive-sequence component, without any response to the negative-sequence component. On the other hand, my previously mentioned copending application showed a network having a strongly weighted negative-sequence response, and a smaller positive-sequence response, either with a strongly weighted zero-sequence response or no zero-sequence response at all.

An object of my present invention is to provide a network which is capable of obtaining the foregoing and other combinations of responses, and of doing so without requiring a three-winding reactor.

With the foregoing and other objects in view, my invention consists in the circuits, systems, combinations, apparatus, parts, and design-methods hereinafter described and claimed, and illustrated in the accompanying drawing, wherein:

Figure 1 is a diagrammatic view of circuits and apparatus illustrative of a fundamental circuit or circuit-principle underlying my invention.

Figs. 2 and 3 are similar views of different alter-

2

native forms of the network, involving variations in the circuits, and

Figs. 4 and 5 are illustrative curve-diagrams which will be referred to in the subsequent description.

My novel sequence-filter network, as shown in Fig. 1, comprises four input-terminals T_1 , T_2 , T_3 and T_0 , two output-terminals F_1 and F_2 , and three impedances $\dot{Z}_1$, $\dot{Z}_2$ and $\dot{Z}_3$. The first three input-terminals, T_1 , T_2 and T_3 , are supplied with a three-phase system of currents $\dot{I}_a$, $\dot{I}_b$, $\dot{I}_c$ or $\dot{I}_a$, $\dot{I}_c$, $\dot{I}_b$. In any event, the phase of the current which is fed in through the first terminal, T_1 , is called phase- a , and the other two phases are supplied to the other two phase-terminals T_2 and T_3 , in either phase-sequence according to the selective sequence-responses which are desired of the network. The last input-terminal T_0 provides a return-path for the neutral-current $3\dot{I}_0$ of a system of star-connected line-currents $\dot{I}_a$, $\dot{I}_b$, $\dot{I}_c$. The three filter-impedances $\dot{Z}_1$, $\dot{Z}_2$ and $\dot{Z}_3$ are respectively connected between the terminals T_1 and T_2 , T_2 and T_3 , and T_3 and T_0 , as shown in Fig. 1. The two output-terminals F_1 and F_2 of the filter as shown in Fig. 1 are connected respectively to the first and last input-terminals T_1 and T_0 , or, in general, so as to be responsive to the vectorial sum of the voltage-drops in the three impedances $\dot{Z}_1$, $\dot{Z}_2$ and $\dot{Z}_3$.

As a consequence of these connections in Fig. 1, the impedance $\dot{Z}_1 = (r_1 + jx_1) = Z_1 \angle \phi_1$ is traversed by the current $\dot{I}_a$; the impedance $\dot{Z}_2 = (r_2 + jx_2) = Z_2 \angle \phi_2$ is traversed by the current $(\dot{I}_a + \dot{I}_b)$ or $(\dot{I}_a + \dot{I}_c)$ according to the phase-sequence of the input-connections; and the impedance $\dot{Z}_3 = (r_3 + jx_3) = Z_3 \angle \phi_3$ is traversed by the zero-sequence current-component $3\dot{I}_0 = (\dot{I}_a + \dot{I}_b + \dot{I}_c)$.

The no-load output-voltage V_F of the filter of Fig. 1 is

$$45 (1) \quad \dot{V}_F = \dot{I}_a \dot{Z}_1 + (\dot{I}_a + \dot{I}_b \text{ or } \dot{I}_a + \dot{I}_c) \dot{Z}_2 + 3\dot{I}_0 \dot{Z}_3$$

$$(2) \quad \dot{V}_F = A\dot{I}_1 + B\dot{I}_2 + C\dot{I}_3$$

50 where the coefficients of the filter-responses to the positive, negative and zero phase-sequence current-components $\dot{I}_1$, $\dot{I}_2$ and $\dot{I}_3$ are respectively,

$$(3) \quad A = A \angle \phi_A = (r_1 + \frac{1}{2}r_2 \pm \frac{1}{2}\sqrt{3}x_2) + j(x_1 + \frac{1}{2}x_2 \mp \frac{1}{2}\sqrt{3}r_2)$$

(4)

$$\dot{B} = B \angle \phi_B = (r_1 + \frac{1}{2}r_2 \mp \frac{1}{2}\sqrt{3}x_2) + j(x_1 + \frac{1}{2}x_2 \pm \frac{1}{2}\sqrt{3}r_2)$$

(5)

$$\dot{C} = C \angle \phi_C = (r_1 + 2r_2 + 3r_3) + j(x_1 + 2x_2 + 3x_3)$$

In Equations 3 and 4, the first of the alternative polarities of $\sqrt{3}$ applies when the second supply-phase is *b*, and the second polarity applies when the second supply-phase is *c*.

In accordance with my invention, the three impedances $\dot{Z}_1$, $\dot{Z}_2$ and $\dot{Z}_3$ are given any magnitudes Z_1 , Z_2 , Z_3 and any phase-angles ϕ_1 , ϕ_2 , ϕ_3 which are necessary to provide (within limits) the desired sequence-responses $\dot{A}$, $\dot{B}$ and $\dot{C}$. In general, my present filter is designed to flexibly or adjustably provide a composite filter-response; that is, a response which is proportional, with different and controllable coefficients $\dot{A}$, $\dot{B}$ and $\dot{C}$, to any two, or all three, of the positive, negative and zero phase-sequence components $\dot{I}_1$, $\dot{I}_2$ and $\dot{I}_0$ of a polyphase current $\dot{I}_a$, $\dot{I}_b$, $\dot{I}_c$.

In my filter-impedances $\dot{Z}_1$, $\dot{Z}_2$ and $\dot{Z}_3$, as shown in Fig. 1, the resistance-parts r_1 , r_2 and r_3 of the impedances are necessarily positive, unless auxiliary insulating-transformers of current-transformers are used, to reverse the direction of current-flow through one or more of the impedances, such as $\dot{Z}_2$ and $\dot{Z}_3$, as indicated, by way of example, at CT_2 and CT_3 in Fig. 3. When this is done, my filter-network may be made to respond to a single one of the rotational phase-sequence components; that is, to either the positive-sequence component $\dot{I}_1$, or the negative-sequence component $\dot{I}_2$, as may be desired.

In general, however, the auxiliary current-transformers CT_2 and CT_3 of Fig. 3 are not used, and hence the zero-sequence network-response $\dot{C}$ will not be zero, because $(r_1 + 2r_2 + 3r_3)$ will always have a finite positive value, in Equation 5.

The three reactance-components x_1 , x_2 and x_3 of the network-impedances $\dot{Z}_1$, $\dot{Z}_2$ and $\dot{Z}_3$ in Fig. 1, may have either positive values, representing inductors or mutual-inductance couplings, or negative values, representing capacitors. As shown in Fig. 2, two-coil mutual-inductance transformers M_1 and M_3 may be used, for, or in, either or both of the end-connected impedances $\dot{Z}_1$ and $\dot{Z}_3$; and the secondary or output-circuit windings of these two-coil reactors M_1 and M_3 may be connected in the output-circuit of VF in either polarity, to provide either positive or negative values of x_1 and x_3 , respectively. The mutual reactors M_1 and M_3 , and the self-inductance coil x_2 , in Fig. 2, have airgap iron cores 4. In general, this method of providing negative values of the reactance-components x_1 and x_3 is preferable to using capacitors. The middle reactance-component x_2 does not generally need to be negative, because the desired response-characteristics can usually be obtained by assigning proper values to x_1 and x_3 to correspond to a zero or positive value of x_2 ; but if a negative value of x_2 is desired, it can best be obtained by using an auxiliary, reverse-connected, current-transformer CT_2 , as shown in Fig. 3.

It will be noted, from Equations 3 and 4, that the third filter-impedance, $\dot{Z}_3$, does not affect the positive and negative responses $\dot{A}$ and $\dot{B}$. Let us first examine, therefore, the relations between the filter-impedances $\dot{Z}_1$ and $\dot{Z}_2$, and the positive and negative phase-sequence responses $\dot{A}$ and $\dot{B}$.

in Equations 3 and 4. The zero-sequence response $\dot{C}$, in Equation 5, may then be given any magnitude C or phase-angle ϕ_C , by assigning proper values to the third impedance $\dot{Z}_3 = (r_3 + jx_3)$.

5 The ratio k of the magnitudes of the negative and positive phase-sequence responses $\dot{B}$ and $\dot{A}$ is a positive number which is given by the equation,

$$(6) \quad k^2 = \frac{B^2}{A^2} = \frac{Z_1^2 + Z_2^2 + (r_1r_2 + x_1x_2) \pm \sqrt{3}(x_1r_2 - r_1x_2)}{Z_1^2 + Z_2^2 + (r_1r_2 + x_1x_2) \mp \sqrt{3}(x_1r_2 - r_1x_2)}$$

$$(7) \quad \therefore Z_1^2 + Z_2^2 + (r_1r_2 + x_1x_2) = \pm \frac{k^2 + 1}{k^2 - 1} \sqrt{3}(x_1r_2 - r_1x_2)$$

$$15 (8) \quad \therefore Z_1^2 + Z_2^2 + Z_1Z_2 \cos(\phi_1 - \phi_2) =$$

$$\pm \frac{k^2 + 1}{k^2 - 1} \sqrt{3}z_1z_2 \sin(\phi_1 - \phi_2)$$

In Equation 8, there are really only three variables. There is the ratio z of the magnitude Z_2 of the second impedance to the magnitude Z_1 of the first impedance. This is a positive number, given by the equation,

$$25 (9) \quad \frac{Z_2}{Z_1} = z$$

Then there is an angle $(\phi_1 - \phi_2)$ by which the impedance-angle ϕ_1 of the first impedance $\dot{Z}_1$ leads the impedance-angle ϕ_2 of the second impedance $\dot{Z}_2$. This gives us a variable, x , which is defined by the two equations,

$$(10) \quad \cos(\phi_1 - \phi_2) = x$$

$$(11) \quad \sin(\phi_1 - \phi_2) = \pm \sqrt{1 - x^2}$$

35 And finally there is a variable K , which is dependent upon the negative and positive response-ratio k which is defined in Equation 6. The variable K is defined by the equation,

$$40 (12) \quad \frac{k^2 + 1}{k^2 - 1} = K = \left(\frac{B^2}{A^2} + 1 \right) / \left(\frac{B^2}{A^2} - 1 \right), \text{ or } k^2 = \frac{K + 1}{K - 1}$$

Making these substitutions in (8), and squaring,

$$(13) \quad (1 + z^2 + zx)^2 = 3K^2z^2(1 - x^2)$$

$$45 (14) \quad \therefore x = \cos(\phi_1 - \phi_2) = \frac{-(1 + z^2) \pm K\sqrt{3z^2(3K^2 - 1) - 3(1 + z^4)}}{z(3K^2 + 1)}$$

50 In Equation 14, either polarity of the plus-or-minus sign $\pm$ may apply, whether the second input-phase is *b* or *c*, because squaring (8) made $(\pm\sqrt{3})^2 = 3$, regardless of the sign.

In order to avoid the square root of a negative quantity, in Equation 14, it is necessary for the impedance-ratio $z = Z_2/Z_1$ to have a value between certain limits, defined as,

$$(15) \quad z^2 > \frac{(3K^2 - 1) + \sqrt{9K^4 - (6K^2 + 3)}}{2}$$

$$60 (16) \quad z^2 < \frac{(3K^2 - 1) - \sqrt{9K^4 - (6K^2 + 3)}}{2}$$

65 The conditions for no response to the positive-sequence component, and for no response to the negative-sequence component, are, respectively,

$$(17) \quad k = \frac{B}{A} = \infty \text{ or } 0$$

$$(17A) \quad \therefore K = \frac{k^2 + 1}{k^2 - 1} = \pm 1$$

$$(17B) \quad \therefore z = \frac{Z_2}{Z_1} = 1 \text{ (from Equation 15 and 16).}$$

$$(17C) \quad \therefore x = \cos(\phi_1 - \phi_2) = -\frac{1}{2} \text{ (from Equation 14).}$$

$$(17D) \quad \therefore (\phi_1 - \phi_2) = \pm 120^\circ$$

Both of the conditions stated in (17B) and (17D) are valid. That is, ϕ_1 may equal either $(\phi_2 + 120^\circ)$ or $(\phi_2 - 120^\circ)$, with the two impedances Z_1 and Z_2 equal to each other in absolute magnitude. In either event, either the negative-sequence response-characteristic B or the positive-sequence response-characteristic A will be zero, depending upon whether the second supply-phase, of terminal T_2 , is b or c . If an auxiliary current-transformer CT_2 (Fig. 3) is to be avoided, it is usually desirable to use the relation $(\phi_1 - \phi_2) = -120^\circ$ in Equation 17D, making ϕ_2 positive, and ϕ_1 negative. However, if the zero-sequence response-characteristic C is to be made zero, an auxiliary current-transformer will be necessary, anyway, as shown at CT_2 or CT_3 in Fig. 3, for supplying current to either all, or a part of, the impedance Z_1 or Z_2 , so as to produce the effect of a negative resistance r_2 or r_3 , and in such a case, $(\phi_1 - \phi_2)$ might as well be $+120^\circ$ as -120° . Two illustrations will suffice.

(17-1) Thus, if $Z_1 = Z_2 = Z$, $\phi_1 = -90^\circ$, and $\phi_2 = 30^\circ$, $r_1 = 0$, $x_1 = -Z$, $r_2 = \frac{1}{2}\sqrt{3}Z$, $x_2 = \frac{1}{2}Z$, $C = (\sqrt{3}Z + 3r_3) + 3jx_3$, and $A = \sqrt{3}Z \angle -60^\circ$ or 0, while $B = 0$ or $\sqrt{3}Z \angle -60^\circ$

according as the second supply-phase is b or c . If the proper values are assigned to the constants, Fig. 2 will depict such a network. If the zero-sequence coefficient C is to be made zero, an auxiliary current-transformer CT_3 may be added, as shown in Fig. 3, to obtain

$$r_3 = -\frac{1}{2}\sqrt{3}Z, \text{ and } x_3 = 0$$

(17-2) Or, if $Z_1 = Z_2 = Z$, $\phi_2 = 82^\circ$, and $\phi_1 = -38^\circ$, $r_1 = .788Z$, $x_1 = -.616Z$, $r_2 = .189Z$, $x_2 = .990Z$, $C = (1.066Z + 3r_3) + j(1.364Z + 3x_3)$, and $A = \sqrt{3}Z \angle -8^\circ$ or 0, while $B = 0$ or $\sqrt{3}Z \angle -8^\circ$

according as the second supply-phase is b or c . If the proper values are assigned to the constants, Fig. 2 will again depict such a network.

In both Case 17-1 and Case 17-2, the relay-response, according to Equation 2, will be

$$(17E) \quad \dot{V}_F = \sqrt{3}(\dot{I}_1Z \angle \phi_A + .577\dot{C}\dot{I}_0 \angle \phi_C)$$

or

$$\sqrt{3}(\dot{I}_2Z \angle \phi_B + .577\dot{C}\dot{I}_0 \angle \phi_C)$$

according as the second supply-phase is b or c in Fig. 2.

When the network responds to both the positive-sequence current-component $\dot{I}_1$, and the negative-sequence current-component $\dot{I}_2$ —that is, when $Z_1 \neq Z_2$, or when $(\phi_2 - \phi_1) \neq \pm 120^\circ$ —then the positive-sequence response-coefficient A will have a phase-angle ϕ_A which leads the phase-angle ϕ_B of the negative-sequence response-coefficient B by an angle $(\phi_A - \phi_B)$ which is given by the equation,

$$(18) \quad T = \tan(\phi_A - \phi_B)$$

$$(19) \quad \therefore T = \frac{\sin \phi_A \cos \phi_B - \cos \phi_A \sin \phi_B}{\sin \phi_A \sin \phi_B + \cos \phi_A \cos \phi_B}$$

$$(20) \quad \therefore T = \frac{\mp \sqrt{3}(Z_2^2 + 2r_1r_2 + 2x_1x_2)}{2Z_1^2 - Z_2^2 + 2r_1r_2 + 2x_1x_2}$$

$$(21) \quad \therefore T = \frac{\mp \sqrt{3}[Z_2^2 + 2Z_1Z_2 \cos(\phi_1 - \phi_2)]}{2Z_1^2 - Z_2^2 + 2Z_1Z_2 \cos(\phi_1 - \phi_2)} = \frac{\mp \sqrt{3}(z^2 + 2zx)}{(2 + 2zx) - z^2}$$

In designing a network to have any required ratio k between the negative-sequence response-coefficient B and the positive-sequence response-coefficient A , it is necessary, first, to calculate K from the required value of $k = B/A$, according to Equation 12 which states that

$$K = \left(\frac{B^2}{A^2} + 1 \right) / \left(\frac{B^2}{A^2} - 1 \right)$$

- 10 It is then necessary to choose an arbitrary value of the impedance-ratio $z = Z_2/Z_1$, which can have any positive value between the limits expressed in Equations 15 and 16, these limits being different for each value of K^2 . It is then necessary 15 to substitute the values of K^2 and z in Equation 14, which will show the impedance-angle-difference $(\phi_1 - \phi_2) = \cos^{-1}x$, which is necessary to produce the required negative-to-positive sequence-ratio k when using the chosen value of the impedance-ratio z .

20 Two illustrative examples are graphically plotted in Fig. 5, in curves x_4 and x_7 , for the values $K^2 = 1.28$ and $K^2 = 1.06$, respectively. When $K^2 = 1.28$, Equation 12 shows that the sequence-ratio k is either 4.03 or 1/4.03; and when $K^2 = 1.06$, k will be either 6.86 or 1/6.86. Whether k is greater or less than unity depends upon whether the second supply-phase is b or c , and whether the impedance-angle-difference $(\phi_1 - \phi_2)$ is positive or negative. Fig. 5 is plotted for negative values of $(\phi_1 - \phi_2)$, or positive values of $(\phi_2 - \phi_1)$, that is, for the case when the impedance-angle ϕ_1 of the first impedance Z_1 is more negative than (or leads) the impedance-angle ϕ_2 of the second impedance Z_2 . When the second supply-phase of the network is b , the conditions shown by the curves x_4 and x_7 in Fig. 5 will produce a sequence-ratio k would be changed to 4.03 and $k = 1/6.86$, respectively, meaning that the positive-sequence response-coefficient A is larger than the negative-sequence response-coefficient B . If the second supply-phase were changed from b to c , or if the impedance-angle-difference $(\phi_2 - \phi_1)$ were changed from positive to negative, the sequence-ratio k would be changed to 4.03 and 6.86, respectively, that is, B would be larger than A ; but if both the phase-sequence of the supply-connections and the sign or polarity of the impedance-angle-difference $(\phi_2 - \phi_1)$ were changed, Fig. 5 would still represent the design-conditions for $k = 1/4.03$ and $k = 1/6.86$, in curves x_4 and x_7 , respectively.

55 From Fig. 5 and Equation 14, it will be noted that the maximum and minimum values of $\pm(\phi_1 - \phi_2) = \cos^{-1}x$ will be obtained when the impedance-ratio $z = 1$, that is when $Z_1 = Z_2$. In such a case,

$$(22) \quad x = \frac{-2 \pm \sqrt{9K^4 - 9K^2}}{3K^2 + 1}$$

60 In curve x_4 , with $K^2 = 1.28$ in Fig. 5, the limiting values of $(\phi_2 - \phi_1)$ are approximately 141.65° and 92.42° , respectively; whereas, in curve x_7 , with $K^2 = 1.06$, the limiting values of $(\phi_2 - \phi_1)$ are approximately 131.3° and 107.3° , respectively.

65 Fig. 5 and Equations 15 and 16 show that the maximum and minimum possible values of the impedance-ratio $z = Z_2/Z_1$ for $K^2 = 1.28$, in curve x_4 , are approximately 1.558 and 0.6417, respectively; whereas, for $K^2 = 1.06$, in curve x_7 , the impedance-ratio z must lie within the limits, $z = 1.234$ and $z = 0.8101$, or $Z_2 = 1.234 Z_1$ and $Z_2 = 0.8101 Z_1$, approximately.

70 For any required value of sequence-response-ratio $k = B/A$, or $K^2 = (k^2 + 1)^2 / (k^2 - 1)^2$, there will

be various values of the phase-angle-difference $(\phi_A - \phi_B)$ between the phase-angles of the positive- and negative-sequence response-coefficients A and B, as shown in Equation 21, which expresses the value of $T = \tan(\phi_A - \phi_B)$. This variation is illustrated in Fig. 4, in the curves T₄ and T₇, which correspond, respectively, to the curves x₄ and x₇ in Fig. 5, for the values, $K^2 = 1.28$ and $K^2 = 1.06$, respectively. Whatever may be the value of K, the angle-difference $(\phi_A - \phi_B)$ between the positive- and negative-sequence coefficients A and B will always be $+120^\circ$ or -60° , when $z = 1$, that is, when the absolute magnitudes Z₁ and Z₂ of the first two network-impedances Z₁ and Z₂ are equal. When z has its maximum value 1.558, when $K^2 = 1.28$, in curve T₄, $(\phi_A - \phi_B) =$ approximately -136.67° , and when z has its minimum value 0.6417, when $K^2 = 1.28$, in the same curve, $(\phi_A - \phi_B) =$ approximately $+16.4^\circ$. When $K^2 = 1.06$, as in curve T₇ in Fig. 4, $(\phi_A - \phi_B) =$ approximately -143.1° when z has its maximum value 1.234, and $(\phi_A - \phi_B) =$ approximately $+23.0^\circ$ when z has its minimum value 0.8101. By choosing different values of z between its maximum and minimum limiting-values, the phase-difference $(\phi_A - \phi_B)$ between the positive-sequence and negative-sequence response-coefficients may be given any value between 0 and 360° .

It should be noted that Equation 21 yields four alternative values of $(\phi_A - \phi_B) = \tan^{-1}T$, for each pair of values of K and z. Which one of these four alternative values is applicable must be determined by substituting each pair of values of K and z in Equations 3 and 4, wherein

$$(23) \quad \cos \phi_A = \frac{r_1 + \frac{1}{2}r_2 \pm \frac{1}{2}\sqrt{3}x_2}{A}$$

$$(24) \quad \sin \phi_A = \frac{x_1 + \frac{1}{2}x_2 \mp \frac{1}{2}\sqrt{3}r_2}{A}$$

$$(25) \quad \cos \phi_B = \frac{r_1 + \frac{1}{2}r_2 \mp \frac{1}{2}\sqrt{3}x_2}{B}$$

$$(26) \quad \sin \phi_B = \frac{x_1 + \frac{1}{2}x_2 \pm \frac{1}{2}\sqrt{3}r_2}{B}$$

using the top sign of the radical $\sqrt{3}$ when the second supply-phase is b, and the bottom sign when the second supply-phase is c. Both the sine and cosine of each angle must be calculated, in order to determine which quadrant the angle is in.

In Fig. 4, it may be noted that changing the sign or polarity of $(\phi_1 - \phi_2)$, without changing its magnitude, makes no difference in $(\phi_A - \phi_B)$; but changing the phase-sequence of the input-currents, that is, changing the second supply-phase from b to c or vice versa, changes the sign or polarity, but not the magnitude, of $(\phi_A - \phi_B)$.

In all of the forms of embodiment of my invention, whether the positive-sequence response is large, small, or zero, or whether the negative-sequence response is large, small, or zero, the zero-sequence response may be given any value at all, whatever may be desired, whether large, small, or zero, and having any phase-angle ϕ_D with respect to the positive- or negative-sequence phase-angle ϕ_A or ϕ_B , by assigning appropriate values to the resistance r_3 and the reactance x_3 which make up the impedance Z₃ in Figs. 1, 2 or 3. The zero-sequence response-coefficient C is as shown in Equation 5. In using this equation, it is necessary to insert the specific values of r_1 , r_2 , x_1 and x_2 which are determined by the required relations

between the positive- and negative-sequence response-characteristics, $k = B/A$ and $(\phi_A - \phi_B)$, as has been described in detail. The proper values of r_3 and x_3 may then readily be determined for giving the zero-sequence response-characteristic C any desired magnitude and phase-angle, in Equation 5.

While I have described the general principles of my invention, and have illustrated the same with a few chosen examples, it is to be understood that my invention is not limited, of course, to the specific and illustrative examples which have been chosen. I desire, therefore, that the appended claims shall be accorded the broadest construction consistent with their language.

I claim as my invention:

1. A sequence-segregating current-network comprising four input-terminals for a three-phase current and a return-current conductor, respectively, two output-terminals, three separate impedances having substantially no mutual reactance therebetween, supply-circuit means associated with the first and second input-terminals for causing one of said impedances to be traversed by an input-current of one phase, supply-circuit means associated with the second and third input-terminals for causing another impedance to be traversed by the sum of that phase and one of the other phases of the input-current, supply-circuit means associated with the third and fourth input-terminals for causing the third impedance to be traversed by the return-current, and output-circuit means associated with the three impedances for causing the two output-terminals to be supplied with the sum of the voltage-drops in the three impedances.

2. A composite sequence-segregating current-network as defined in claim 1, in which the three impedances have such values as to produce an output-voltage which is responsive to a plurality of the phase-sequence components of the three-phase input-current.

3. A network as defined in claim 1, characterized by the three impedances having the values

$$Z_1 = Z_1 \angle \phi_1 = r_1 + jx_1, Z_2 = Z_2 \angle \phi_2 = r_2 + jx_2,$$

and
 $Z_3 = Z_3 \angle \phi_3 = r_3 + jx_3$, respectively, in which the ratio, $z = Z_2/Z_1$, of the first two impedances, and the phase-angle-difference, $(\phi_1 - \phi_2) = \cos^{-1}z$, between them, are related to each other, and to the desired network-constant, $K = (k^2 + 1)/(k^2 - 1)$, where $k = B/A$ is the ratio between the magnitude of the desired negative-sequence response B and the magnitude of the desired positive-sequence response A, by the formula,

$$x = \cos(\phi_1 - \phi_2) = \frac{-(1+z^2) \pm K\sqrt{3z^2(3K^2-1)-3(1+z^4)}}{z(3K^2+1)}$$

for any chosen value of z, chosen between certain limits, defined as

$$z^2 \neq \frac{(3K^2-1) + \sqrt{9K^4-(6K^2+3)}}{2}$$

and

$$z^2 \neq \frac{(3K^2-1) - \sqrt{9K^4-(6K^2+3)}}{2}$$

and the third impedance, Z₃, has whatever value may be needed, with the values of Z₁ and Z₂ thus obtained, to provide the desired zero-sequence response,

$$C = (r_1 + 2r_2 + 3r_3) + j(x_1 + 2x_2 + 3x_3)$$

4. The invention as defined in claim 1, including means for reversing the polarity of the voltage-drop across a portion or all of one or more of the impedances included in the network.

5 WILLIAM K. SONNEMANN.
